(57) **CLAIM**

The ornamental design for a lamp, as shown and described.

DESCRIPTION

FIG. 1 is a perspective view of a lamp, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view of a lamp; and,

FIG. 9 is a perspective view of second embodiment of a lamp in accordance with our new design.

The portions of the lamp in FIG. 9, shown in broken lines, represent environmental structure and form no part of the claimed design.

1 Claim, 6 Drawing Sheets
